ELECTRIC SIGNAL SYSTEM

Filed Aug. 8, 1927

INVENTOR
THOMAS H THOMAS
BY *John H. Brady*
ATTORNEY

UNITED STATES PATENT OFFICE.

THOMAS H. THOMAS, OF EDGEWOOD, PENNSYLVANIA, ASSIGNOR TO THE WESTINGHOUSE AIR BRAKE COMPANY, OF WILMINGTON, PENNSYLVANIA, A CORPORATION OF PENNSYLVANIA.

ELECTRIC SIGNAL SYSTEM.

Application filed August 8, 1927. Serial No. 211,377.

This invention relates to signal systems and more particularly to an electric signal system adapted for use on railway trains.

An object of my invention is to provide an electric train signal system by the use of which a trainman may signal the engineman from any car of a train and by which the engineman's reply signal will be received by the trainman only at the station from which the signal was sent by the trainman or at any other station or stations the trainman may choose.

In the accompanying drawing, Fig. 1 is a diagrammatic view of an electric signal system embodying my invention, and illustrating the engineman's switch in one position, and Figs. 2 and 3 are diagrammatic sectional views showing the engineman's switch in two other positions.

As illustrated in the accompanying drawing, the locomotive or controlled car of a train may be provided with an electric battery 1 or any other desired source of electric current, a signal indicating device such as a buzzer 2 and an engineman's switch 3 comprising a rotatable member 4 which is provided with a contact 5 adapted in one position to electrically connect terminal contacts 6 and 7 which are connected to ground at 8 and to one terminal of the buzzer 2, respectively, and in another position to electrically connect terminal contacts 9 and 10, which are connected to the positive terminal of the battery 1 and to a train wire 11, respectively. The negative terminal of the battery 1 is connected to ground at 12. The train wire 11 is connected to the other terminal of the buzzer 2.

Each of the cars of a train may be provided with an electric battery 12 or any other suitable source of electric current, a signal indicating device such as a buzzer 13, a switch device 14 and a jack device 15.

The switch device 14 comprises a casing 16 containing a sliding contact member 17, which member is provided with an operating stem 18 adapted to be operated, in one direction, by a lever 19 having operating arms 20 and 21, each having an operating cord 22 attached thereto. This lever 19 is adapted to fulcrum around pins 23 and 24 which are so disposed and mounted in the casing 16, that when the arm 20 is operated the lever turns about the pin 23 and when the arm 21

is operated the lever turns about the pin 24 and in either case the lever depresses the stem 18 and the contact member 17, rotative movement of the member being prevented by a pin mounted in the casing engaging in a slot formed in the member.

The member 17 is provided with a contact 25 and is normally maintained in the position shown in the drawing by the action of a spring 26. When the member 17 is moved, by the lever 19, a predetermined distance, the end of said member will engage a stop formed on a plug 27 having screw-threaded connection with the casing 16. When the member 17 is in this position the contact 25 will connect terminal contacts 28 and 29 connected to the positive terminal of the battery 12 and to a tine 30 of the jack 15, respectively. The negative terminal is connected to ground at 31.

The jack 15 is also provided with tines 32 and 33 which are connected to one terminal of the buzzer 13 and to the ground at 34, respectively. The other terminal of the buzzer is connected to the train wire 11. The tines 30 and 32 of the jack, normally contact with each other and are so formed that they are adapted to receive the end portion of a plug 35 between them. The tine 33 is normally out of contact with the tine 32, but when the plug 35 is inserted between the tines 30 and 32, the tine 32 is moved into contact with the tine 33.

Assuming the several parts of the signal system to be in the positions as shown in Fig. 1 of the drawing, and the trainman desires to signal the engineman, the trainman pulls the cord 22 which causes the lever 19 to operate to depress the stem 18 and contact member 17 a sufficient distance that the lower end of the member engages the stop on the plug 27 secured to the casing 16, in which position the contact 25 electrically connects the terminal contacts 28 and 29 and as the tines 30 and 32 of the jack 15 are in contact with each other, and the contact 5 of the engineman's switch 3 connects the terminal contacts 6 and 7, current will flow from the positive terminal of the battery 12, through the buzzer 13, train wire 11, buzzer 2 and switch 3 to ground at 8, and as the negative terminal of the battery is connected to ground at 31, the circuit is complete and both buzzers will operate. While the train-

man maintains the contact member 17 depressed, the engineman may signal the trainman by rotating the member 4 so that the contact 5 will be moved out of engagement with the terminal contact 6 which leads to ground, as shown in Fig. 2 of the drawing, thus opening the circuit and interrupting the operation of the buzzers. By rotating the member 4 back and forth, the circuit is opened and closed, so that the engineman may thus cause any predetermined signal to sound at the trainman's station on the train.

With the several parts of the signal system in the positions as shown in Fig. 1 of the drawing, and the trainman desires the system to be in readiness that he might receive, at his station on the train, any signal which may be initiated by the engineman, he inserts the plug 35 between the tines 30 and 32 of the jack, which causes the tine 32 to move into contact with the tine 33 of the jack, thus connecting one terminal of the buzzer 13 to ground at 34. If the engineman wishes to signal the trainman, he rotates the member 4 of the switch 3 to the position as shown in Fig. 3 of the drawing, in which position, the contact 5 connects the terminal contacts 9 and 10, thus permitting current to flow from the positive terminal of the battery 1, through the switch 3, train wire 11, buzzer

13, and jack 15 to ground at 34, and as the negative terminal of the battery 1 is connected to ground at 12, a circuit is completed and the buzzer 13 will operate.

Having now described my invention, what I claim as new and desire to secure by Letters Patent, is:—

In a train signal system, the combination with a train wire, of a signaling unit on one car of a train comprising a signal device connected to said train wire, a source of electric current, and a switch device having one position for connecting said source to said train wire and another position for connecting said signal device to ground, and another signaling unit on another car of the train comprising a second signal device connected to said train wire, a second source of electric current, and two switch devices, one of said switch devices having a position for connecting said second source of current to said second signal device and the other switch device having a position for connecting said second signal device to ground and for opening the circuit through which said second signal device is connected to said second source of current.

In testimony whereof I have hereunto set my hand.

THOMAS H. THOMAS.
